UNITED STATES PATENT OFFICE

ALBERT F. BEMIS, OF NEWTON, MASSACHUSETTS, ASSIGNOR TO BEMIS INDUSTRIES, INC., OF BOSTON, MASSACHUSETTS, A CORPORATION OF DELAWARE

BUILDING CONSTRUCTION

Application filed May 13, 1927. Serial No. 191,044.

This invention relates to an improved building construction and in some aspects comprises an improvement upon the subject matter of my copending application, Serial No. 149,755, filed November 20, 1926.

This construction utilizes preformed or standardized units which may be assembled in situ and which are adapted to receive cementitious material poured therebetween in order to provide an unusually strong and rigid wall structure, the arrangement and design of the parts permitting the ready installation of floors, roofs and the like and the securing of doors, windows or the like in place in the walls. The standardized parts may be made of comparatively light material and with normal dimensions so that they may be easily transported and assembled and are so designed that comparatively little skill is required in bringing them into proper alignment or interfitting relation. Thus the cost of labor as well as the cost of materials for a building of this character may be comparatively low. This type of building construction permits rapidity in construction and the ready application of plaster, stucco or the like to the walls without the need of furring or lathing in order properly to hold the plaster or stucco in place. The resulting building may be of semi-fireproof or fire-proof construction and is unusually sturdy and rugged. The walls have highly satisfactory acoustic properties whereby resonance is avoided and sound tends to be absorbed, and are substantially impervious to the attacks of moisture or vermin.

This type of building construction is designed to utilize preformed slabs of heat-insulating material, preferably matted fibrous material which may be in the form of elongate fibrous strips of small cross section, e. g., excelsior or the like, bound together with appropriate cementitious material, not only to hold the fibrous strips in firmly bound meshed or reticulated engagement but also to render the same substantially fireproof and moisture-proof. Preferably these slabs are of ribbed formation being provided with corrugated or undulatory surfaces, individual undulations being separated by uniformly

spaced grooves of a defined width. The material is loosely matted to provide numerous insulating spaces or air cells and is of comparatively light weight so that it may be readily handled. Preferably the undulatory surfaces are so arranged as to provide the slabs of fibrous material with portions of different thicknesses, the amount of material in the various parts of the slab being substantially the same, but the fibrous elements being more loosely matted at the parts of the slab between the grooves so that these portions of the slab are provided with additional heat-insulating qualities and are adapted more effectively to interlock with cementitious material poured into engagement with the same. Material of this character is adapted to permit the setting of concrete or the like under the most satisfactory conditions, since the excess water of plasticity will at first be taken up from the concrete and will later be absorbed by the same as setting continues.

The above and further objects and advantages of the invention will be apparent to those skilled in the art upon a reading of the subjoined description and claims in conjunction with the accompanying drawings, in which:

Fig. 1 is a broken vertical section through a portion of a house built in accordance with the form of building construction disclosed herein;

Fig. 2 is a sectional detail;

Fig. 3 is an isometric view of a portion of the building, parts being removed and parts being broken away;

Fig. 4 is a similar view of another portion of the building;

Fig. 5 is a horizontal section of an outer corner of the building;

Fig. 6 is a horizontal section through a portion of the building wall adjoining a door or window frame;

Fig. 7 is a horizontal section through a joint between walls of the building;

Fig. 8 is a similar view of the intersection of walls;

Fig. 9 is a detail isometric view of a portion of the preferred form of slab used for a building construction of this type;

Fig. 10 is an enlarged cross section of the same;

Fig. 11 is a sectional detail; and

Fig. 12 is a section on line 12—12 of Fig. 1.

A building of the type disclosed in the accompanying drawings may preferably be erected upon a foundation 1 of cementitious material such as concrete. When this foundation is poured, dowels 2 are located in its upper surface at appropriate points where uprights or posts are subsequently to be erected. Furthermore, suitable bolts 3 may be embedded in the foundation and project upwardly therefrom in order to engage sill members 5 which may extend along the inner portions of certain parts of the foundation to provide means for securing the lower floor joints 25 thereon.

Suitable posts 8, 9, 10, 11 of wood, metal, cementitious material, or the like are preformed with standardized dimensions and are located at the corners of walls, wall intersections, or at the sides of door or window casings. These posts preferably have recesses 12 formed in their lower ends which are adapted to engage the dowels or pins 2 projecting from the foundation 1, so that the posts may quickly be erected or located substantially in an upright position merely by engaging recesses 12 with dowels 2 (Fig. 11).

Posts 8 which are located at the corners of walls preferably are of L-shaped cross section, as disclosed more particularly in Figs. 3 and 5. Posts 9, which are located adjoining door or window casings, may be of rectangular section, as shown; posts 10 which are located at the intersection of walls may be of T-shaped section, as shown in Fig. 7, while posts 11 at the intersection or crossing of walls may be of cross-shaped section, as shown. These posts preferably correspond in heights substantially to the height of a story of the building to be erected and may be formed of wood, metal or other suitable material.

Along the upper ends of the posts I secure suitable girt ties 26, thereby forming a braced skeleton frame. Preferably these girt ties are in the form of a pair of elongate strips superimposed upon each other and provided with registering openings 19 for purposes which will presently be described.

After the posts for a wall portion have been erected in the manner indicated, I preferably secure the lower course of slabs 15 thereto. The construction of these slabs is illustrated more in detail in Fig. 9. Preferably the slabs are formed of elongate strips of ligneous material of small cross section, such as excelsior formed by knifing pieces of wood into small strips. The fibrous material is loosely matted and may have portions lightly compressed while it is impregnated with a suitable cementitious agent which prefer-

ably renders the material fire resistant and moisture resistant; magnesite cement being one of the materials which has been evolved for this purpose.

These slabs preferably are formed with corrugations or undulatory portions 17 in which the fibrous material is very loosely matted. Between the undulatory portions 17 are the grooves 18 which may provide surfaces substantially parallel to the opposite flat faces of the slabs. The same amount of material is used throughout substantially all portions of the slab, but, at the points of greatest thickness formed by the undulations 17, the material is more loosely matted than adjoining the grooves 18. Thus the undulations 17 provide portions of the slab with additional heat-insulating and sound-absorptive properties and permit these portions of the slab to have a secure interlocking engagement with cementitious material poured against the same, while the more closely compacted portions 11 provide the slabs with sufficient structural strength and are adapted to engage studs in the manner indicated below.

The lower course of slabs 15 may be loosely secured to the posts 8, 9, 10 or 11, the slabs preferably having such a length that end portions thereof engage the posts. Preferably, slabs of this character are preformed of standardized dimensions and are especially useful in building constructions in which the posts are arranged at appropriate multiples of modular distances, corresponding to the spacing of the grooves 18 upon the slabs, so that provision of only a few sizes of slabs is necessary in order to fulfill the requirements of any given building construction. It is to be understood, however, that the preferred materials from which the slabs 15 are made permit of ready cutting or sawing of the same.

When the lower course of slabs is first secured upon the upright posts the slabs preferably are rather loosely assembled upon the posts. One convenient method of doing this is to nail or otherwise secure the slabs to one side of the posts, for example, the slab upon the inner side of the wall under construction may be nailed against the posts in the conventional manner, while the slab upon the outer face of the wall under construction may be loosely secured to the post by only securing it by one nail passing through the lower portion of the slab so that the upper edge of the slab may be moved outward somewhat in relation to the post and the adjoining slab. Thereupon, studs 20, which are of standardized cross section, and which may be of wood, metal or the like, are assembled upon the foundation 1, the grooves 18 upon the opposite slabs being adapted to engage the studs and the loose arrangement of one of the slabs being adapted to permit ready insertion of the stud in substantial alignment with adjoining studs. Thereupon, the loosely mounted slab

is brought into firm engagement with the posts, and both slabs are firmly secured to the studs. Succeeding courses of slabs are then attached to opposite faces of the studs and posts until the construction reaches the height of approximately one story, whereupon the outer layer of slabs may be continued upward above the girt ties 26, as designated by numeral 27.

10 The floor joists 29 for the second floor may be located upon the girt ties 26 in the manner shown. Between these floor joists I may locate certain spacer or form boards 31 (Fig. 1). These form boards cooperate with ends of 15 joists 29 and with the outer course of slabs 27 to provide a form for pouring cementitious material, such as concrete. This material may then be poured between members 27 and 31 and will pass through openings 19 into the 20 spaces between the inner and outer layers of slabs and the adjoining studs so that a substantially monolithic concrete structure is provided into which the ends of the joists are keyed.

25 The girt ties 26 may be provided with suitable pins corresponding to pins 2 in the foundation to engage the posts for the second story, which is erected in a manner analogous to that described with reference to the first 30 story, except that the cementitious material may not reach higher than the upper portion of the slabs and that the girt ties 49 at the top of the second story, assuming that a two-story building is being built, fill substantially 35 the full width of the wall.

In order to provide continuous surfaces upon the building walls for the application of any suitable finishing material such as plaster or stucco, I provide suitable filler slabs 40 which are shaped to fill the spaces between the ends of standard slabs 15 adjoining posts 8, 9 and 10.

A building construction of this type has many advantages, being inexpensive and requiring the minimum of time and of skilled labor upon the building site in the erection of the building construction. The standardized posts and studs are comparatively light and are easily assembled in position. The 50 slabs 15 are very light and are shaped to facilitate alignment of the studs in position as well as being more firmly secured thereto, due to their interfitting engagement therewith and coincidentally the studs serve properly to align or locate the slabs. The matted formation of the slabs provides the walls with excellent heat-insulating and sound-absorptive properties and is adapted to cause the setting of the intermediate concrete layer

55 in the best possible manner, not only interlocking with the concrete to form a firm bond therewith, but taking up the superfluous water of plasticity when the concrete is first poured without carrying the same outward 60 to the outer faces of the wall, and giving up

this water again to the concrete when setting has but partially finished.

A building of this type is adaptable to the various modifications and use with the various factors usually incorporated in a building, for example, Fig. 2 shows the location of a partition upon a concrete wall 201, suitable sills 202 being bolted to the wall in the manner described with reference to the foundation 1 and sills 2 of Fig. 1. Upon these 70 sills the floor joists 24 are located in the conventional manner, while a space is provided therebetween for the interposition of slabs 29 and the formation of a wall similar to that previously described. Obviously, certain 75 spaces between certain studs may be left free of cementitious material, if desired, in order to provide a lighter and more economical construction, such an arrangement being 80 more suitable for interior partitions.

Fig. 6 discloses the arrangement of the wall at the door or window casing, the filler slabs being located upon each face of the post 9 and the edge of this post being adapted to receive the casing nailed thereto. The spaces 85 between the edges of the filler slabs and the casing may be filled with plaster or stucco designated by numerals 29 and 30, respectively, these stucco and plaster layers being applied to the wall by a gun or in any conventional manner.

While my disclosure shows excelsior slabs, wood studs and posts and concrete poured between the slabs, it should be understood that the slabs may be of any other light material so long as they are essentially of the shape disclosed in Fig. 9, that studs, posts and joists may be of steel, precast concrete, gypsum, lumber or the like, and that any cementitious material may be poured in the 95 spaces between the slabs.

I claim:

1. A wall construction comprising a row 100 of parallel studs, slabs at either side of the studs, said slabs being formed with grooved undulatory inner faces which provide grooves in interfitting engagement with said studs.

2. A wall construction comprising a row 110 of parallel studs, slabs of loosely matted fibrous material at either side of the studs, said slabs being formed with grooved undulatory inner faces which provide grooves in interfitting engagement with said studs.

3. A wall construction comprising a row 120 of parallel studs, slabs of loosely matted fibrous material at either side of the studs, said slabs being formed with grooved undulatory inner faces which provide grooves in interfitting engagement with said studs, the 125 matted fibrous material being more compactly arranged adjoining said grooves than between the same.

4. A wall construction comprising a row 130 of parallel studs, slabs of heat-insulating ma-

terial at either side of the studs, said slabs being formed with grooved undulatory inner faces which provide grooves in interfitting engagement with said studs, and cementitious material located between said slabs.

5. A wall construction comprising a row of parallel studs, slabs of loosely matted fibrous material at either side of the studs, said slabs being formed with undulatory inner faces which provide grooves in interfitting engagement with said studs, and cementitious material poured in certain of the spaces defined by adjoining studs and opposed slabs, said cementitious material having a firm interlocking engagement with loosely matted material of the slabs.

6. A wall construction comprising a row of parallel studs, slabs at either side of the studs, said slabs being formed with undulatory inner faces which provide grooves in interfitting engagement with said studs, and cementitious material poured in certain of the spaces defined by adjoining studs and opposed slabs, said slabs having rough surfaces in firm interlocking engagement with the cementitious material.

7. A wall construction comprising a row of parallel studs, slabs of loosely matted fibrous material at either side of the studs, said slabs being formed with undulatory inner faces which provide grooves in interfitting engagement with said studs, and cementitious material poured in certain of the spaces defined by adjoining studs and opposed slabs.

8. A wall construction comprising a row of parallel studs, slabs at either side of the studs, said slabs being formed of loosely matted elongate fibrous strips bound by an adhesive impregnating agent, said slabs being provided with undulatory inner faces which comprises grooves in interfitting engagement with said studs.

9. A wall construction comprising a row of parallel studs, slabs at either side of the studs, said slabs being formed of loosely matted elongate fibrous strips bound by an adhesive impregnating agent, said slabs being provided with undulatory inner faces which comprise grooves in interfitting engagement with said studs, said impregnating agent serving to provide a non-moisture absorbing, substantially fire-proof coating for the slabs.

55 10. The method of building construction which comprises the provision of a fundation, the location of upright posts upon the fundation, securing a lower course of grooved slabs in loose engagement with opposite faces of the posts, locating studs in alignment at appropriate intervals upon the fundation by engaging them in certain grooves, of said slabs, securing the lower slabs firmly to the posts and to the studs thereby bringing the parts accurately into alignment, and securing additional courses of slabs to the studs.

parts accurately into alignment, and securing additional courses of slabs to the studs.

11. A method of building construction which comprises the provision of a fundation, the location of pins at modular distances upon said fundation to engage recesses in upright posts, the location of upright posts upon the fundation, securing of a lower course of grooved slabs in loose engagement with opposite faces of the posts, locating studs in alignment at appropriate intervals upon the fundation by engaging them in certain grooves upon said slabs, securing the lower slabs firmly to the posts and to the studs thereby bringing the parts accurately into alignment, and securing additional courses of slabs to the studs and posts.

70 12. The method of building construction which comprises the provision of a fundation, the location of upright posts upon the fundation, securing of a lower course of grooved slabs in loose engagement with opposite faces of the posts, locating studs in alignment at appropriate intervals upon the fundation by engaging them in certain grooves, upon said slabs, securing the lower slabs firmly to the posts and to the studs thereby bringing them accurately into alignment, and securing additional courses of slabs to the studs, mounting rangers with openings therein registering with spaces between slabs upon the upper ends of said studs and pouring cementitious material through said openings into said spaces.

75 13. The method of building construction which comprises the provision of a fundation, the location of upright posts upon the fundation, securing of a lower course of grooved slabs in loose engagement with opposite faces of the posts, locating studs in alignment at appropriate intervals upon the fundation by engaging them in certain grooves upon said slabs, securing the lower

80 slabs firmly to the posts and to the studs thereby bringing them accurately into alignment and securing additional courses of slabs to the studs, mounting rangers with openings therein registering with spaces between slabs upon the upper ends of said studs and pouring cementitious material through said openings into said spaces, and forming another story by locating posts and studs above

85 said rangers, locating a course of slabs upon the outer side of the wall adjoining said rangers, placing the ends of floor joists upon the inner edges of the rangers, locating form and space members between the ends of said rangers and having cementitious material between said slabs and form boards at the ends of said joists.

90 14. A slab comprising matted strands of fibrous material held together by a cementitious binder, said slab having a flat face and an opposite face having parallel depressions which are spaced by bulging portions

100

105

110

115

120

whereby the slab is provided with a plurality of parallel regions of minimum area, the matted material being substantially uniformly distributed throughout these portions,
5 whereby the strands are loosely matted in the bulging portions to permit ready interlocking with poured cement or the like and whereby the depressed portions are adapted more readily to receive and hold nails to secure the
10 slabs to frame elements engaging these portions.

15. A slab comprising matted strands of fibrous material held together by a cementitious binder, said slab having a flat face and an opposite face having parallel depressions with flat faces in parallelism with the flat face of the slab, said depressions being spaced by bulging portions whereby the slab is provided with a plurality of parallel regions of
20 minimum area, the matted material being substantially uniformly distributed throughout these regions, whereby the strands are loosely matted in the bulging portions to permit ready interlocking with poured cement or
25 the like and whereby the depressed portions are adapted more readily to engage and be secured to frame elements.

Signed by me at Boston, Massachusetts this eleventh day of May, 1927.

30 ALBERT F. BEMIS.
